FAN

George de Bothezat, New York, N. Y., assignor to
 American Machine and Metals, Inc., New York,
 N. Y., a corporation of Delaware

Application September 8, 1931, Serial No. 561,524

12 Claims. (Cl. 230—123)

This invention relates to rotary fans and particularly to fans for delivering a gas such as air in large quantities and against considerable resistance.

5 The object of the invention is to provide such a fan of simple compact structure and high efficiency, the fan comprising a plurality of oppositely rotating impellers of the disk type cooperating in sequence to move a continuous stream of air or other gas at desired velocity and pressure.

10 Another object of the invention is to provide a fan capable of very quiet operation while at the same time giving good air deliveries and high static pressures.

15 Further objects of the invention particularly in the details of the impellers and driving means will appear from the following specification taken in connection with the accompanying drawings in which

20 Fig. 1 is an end view of a fan unit,

Fig. 2 is a vertical sectional view of the same with parts broken away.

25 Figs. 3, 4 and 5 are diagrammatic views illustrating the blade action of the impellers,

Fig. 6 is a sectional view of an impeller showing the hub and blade structure,

Figs. 7 and 8 are views similar to Fig. 2 but illustrating modifications,

30 Fig. 9 is an end view of a modified form of apparatus, and

Fig. 10 is a corresponding side view of the same with parts broken away,

Fig. 11 is an end view of a further modification, and

35 Fig. 12 is a side view of the same with parts broken away.

In the embodiment of the invention shown in Figs. 1 and 2 a cylindrical housing 10 is provided

40 having a central stay or support 11 carrying spindles 12 upon which are rotatably mounted the cooperating fan impellers F, F'.

The housing 10 has the rings 14 at the ends connected by longitudinal bolts 15 passing through the bushing spacers 16, giving a very light sturdy structure to

45 the housing as a whole. A driving motor 17 is mounted on top of the housing, carrying the pulleys 18 and 19 at the opposite ends of the shaft,

the pulley 18 driving the pulley 20 of rotor F and the pulley 19 driving the pulley 21 of the rotor F'

50 by means of a reverse idler combination, described and claimed in my copending application Serial No. 514,505. A separate housing 22 may be provided for the motor drive comprising the end plates 23 and side plates 24 flanged and fastened

5 The air is drawn inward at the left (Fig. 2) and compressed somewhat and delivered by the impeller F into the space between the impellers where it is picked up by the impeller F' and further compressed and delivered in a continuous stream from the right or outlet end of the housing.

10 By proper design and operation of the impellers F, F', high efficiency of the unit may be assured so as to give a smooth continuous handling of 10 large quantities of air against considerable resistance. In order to bring about a proper co-operation between the successive impellers F, F', it is necessary to conform to the basic principles 15 of air resistance or more generally fluid resistance in connection with the impeller vanes or blades.

15 If an aerofoil blade (Fig. 3) has directed on it an air stream with velocity W, the resultant pressure R of the air (the air resistance) is proportional generally to the angle of attack or incidence under which the stream meets the aerofoil and the square of the velocity W. If, however, there are a number of aerofoils (Fig. 4) in a row on which a stream of velocity W' is directed, then the air resistance R of each aerofoil of the row is not proportional to W', but is proportional to a velocity W, which is the geometric mean of W' and the velocity W'' behind the aerofoils; this is half the geometric sum of W' and W''. When only a single aerofoil is 30 disposed in an air stream as in Fig. 3, the stream as a whole is not deflected downward behind the aerofoil, the so-called down wash in this case being only a local phenomenon affecting part 35 of the stream only. But in the case of a row of aerofoils (Fig. 4) spreading across the stream, the whole of the stream is deflected and the amount of this deflection depends upon the spacing of the aerofoils. The more aerofoils there 40 are in the stream, up to a certain limit, the smaller the spacing of the aerofoils will be and the greater will be the stream deflection produced by the aerofoils. The air resistance R of each aerofoil will be related to the amount of 45 deflection the stream undergoes so that the resistance R depends not only upon the entering velocity W', but also upon the discharge velocity W''. As above pointed out, this resistance R will be proportional to the square of the geometric mean W of W' and W''. If the blades of 50 the disk fan are cut by a coaxial cylinder, and the cross section is developed in a plane, the blade cross sections will constitute a row of aerofoils so that the law of air resistance for the fan 55

blades will correspond to that of a row of aerofoils.

If there are two disk fans coaxial and rotating in opposite directions so that both are operating 5 in the same slip stream (the stream created by a rotating blade screw being usually called slip-stream), and if as shown in Fig. 5 the aerofoil cross sections represent one blade of each of the disk fans taken at a distance r from the fan 10 axis and if Ω is the angular velocity of rotation, assumed equal but of opposite sense, for both fans, then the air stream in passing the fan F will acquire an angular velocity ω' , and after 15 passing fan F' the air may still have an angular velocity ω'' (all these assumptions being referred to a distance r from the fan axis).

The impellers F , F' may be so formed and related that the first impeller F will impart to the stream a rotational component which will be reduced to zero by the action of the second impeller F' so that ω'' equals zero, then there is 20 no rotation of the final air stream, and there will be no rotational losses in the discharge. The losses are thus confined to the blade losses, 25 pact, friction and the like, and high efficiency will be attained. According to the theorem of moments of momentum, the rotating effect of fan F will be counteracted by fan F' when the torques applied to each of the fans are equal in 30 magnitude but opposite in direction. Then the slip-stream leaving fan F' will have no rotation because each fan communicates to the air stream equal opposite rotation momentum, and thus the resulting rotation behind the second fan F' will 35 be zero.

The conditions under which impellers F , F' operate are not identical, and there is, therefore, required a complementary change in the characteristics of these impellers in order that they 40 shall have equal torques under these different conditions. The relative velocity W_1 —to be used to estimate the air resistance on each blade of fan F —is the resultant of the axial stream velocity v and the velocity $r\Omega - r\omega = r(\Omega - \omega)$, where 45 ω equals one half ω' . But the relative velocity W_2 for the second fan F' is the resultant of v and $r(\Omega + \omega)$. It thus follows that the magnitude of W_2 is larger than the magnitude of W_1 or $W_2 > W_1$ but the angle of W_2 with the plane of 50 rotation of fan F' is smaller than the angle of W_1 with the plane of rotation of fan F . Now if the angle of attack of the blades of each fan 55 in relation to W_1 and W_2 respectively is substantially the same, in order to have the torques equal, fan F' must have a smaller total blade area than fan F or a smaller number of blades if both fans have blades of equal size. In addition, since it is desirable to have the angles of attack substantially the same, the blade angles ϕ_1 of the 60 blades of fan F must be larger than the blade angles ϕ_2 of the blades of fan F' . Only under these conditions can the resultant pressure on the blades be equal, the torques being proportional to these resultant pressures.

65 Therefore, a set of two coaxial disk fans rotating in opposite directions in their mutual slip stream will have highest efficiency when the slip stream behind the second fan F' does not rotate. This condition of no rotation will be realized 70 when the torques applied to the fans F , F' are equal in magnitude and opposite in direction, and this equality of torques can only be realized—for two fans rotating at the same speed—when the first fan has more blades than the second, in case 75 of blades of equal width, and the blade angles of

the blades of the first fan F are larger than the blade angles of the blades of the second fan, these blade angles being taken with respect to the plane of rotation.

Since as above explained the rotational energy 5 communicated to the air by the first impeller can be fully recovered by the second impeller, it is advantageous to form the blading of the first impeller to impart a high rotational component 10 to the stream, thus giving the discharge from the first impeller F additional energy. To achieve this, very high blade angles are used in the first impeller F , generally higher than 45°, and the second impeller F' , as explained above, 15 has a smaller blade angle, as a rule smaller than 45°. In this way the air drawn in by the first impeller F of the pair has imparted to it not only the full axial velocity required for the desired 20 delivery, but also a very high angular velocity around the axis so that the resultant stream line, particularly in the outer portions of the flow, may be at an angle as high as 45°, as shown by a thread line interposed in the stream. This means greatly increased efficiency for the first impeller calculated on the basis of a total energy delivered 25 to the discharge. Ordinarily, a large proportion of the energy of this whirling discharge would be lost in useless turbulence due to the whirl. With a properly designed and cooperating second impeller F' , however, this whirl is effectively and 30 efficiently recovered so that the final discharge is substantially axial in direction, and the high whirl of the flow entering the second impeller enables it to also operate very efficiently on the 35 stream as a whole so that the combined effects of the two impellers represent increase in efficiency over that attainable by a single impeller producing the same delivery against the same pressure.

The above conclusions have been tested and 40 confirmed and high efficiencies, substantially 90%, have been attained, and it is found that the static pressure developed by a properly cooperating pair of disk impellers and the air volume delivered thereby are substantially double the pressure and delivery of a single disk impeller of the same diameter and speed. Both the pressure and the volume are doubled.

Consequently, good air deliveries and high 45 static pressures are attainable at relatively low 50 speeds, resulting in the very important characteristic of quietness in operation. The cooperating series of impellers thus build up pressure from stage to stage while efficiently and silently passing large quantities of air by impeller-blower action. 55

In Fig. 6 one form of construction of the impeller is shown built up of four parts. The hub 27 carries the blade 28 by means of the connecting disks 29. The blades 28 are bent to form flanges fitting between the disks 29 and riveted thereto as indicated at 31, while the inner portions of the disks 29 are fastened to the flange of the hub 27 by the through rivets 30.

In the modification shown in Fig. 7 there are a 65 series of impellers I, II, III and IV receiving the air flow at the left and discharging it at the right. The impellers I and IV are mounted on one shaft 35 passing through a hollow shaft 36 on which are mounted the impellers II and III. Bearings 37 and 38 of stays 39 and 40 support the shaft. The hollow shaft 36 is either mounted on the shaft 35 or on bearings supported from the stays 39 and 40 at each end. The impellers I and IV are driven by pulley 41 belted to the pulley 42 at the left end of the motor 43, the pulley 44 at the 70 71

right end of the motor being belted to the pulley as high as 45°. The energy from the first impeller is thus converted into pressure and velocity in its discharge and with the velocity energy relatively high due to the high rotational components. Then the second impeller recovers this rotational energy and finally delivers the air under increased pressure and with the discharge substantially axial in direction. 5

10 so that pulleys 41 and 45 are driven in opposite directions. For small powers a cross belt could be used instead of the reversing idlers. This construction provides two pairs of impellers with the members of each pair rotating in opposite directions. The impellers II and III have the same direction of rotation, this being unobjectionable because there is little or no rotation of the air flow between them, since impeller II substantially neutralizes any component of angular

15 velocity imparted to the flow by the impeller I.

In Fig. 8 a modification is shown providing for six or eight impellers in series. Impellers I, IV, V and VIII are mounted on one shaft 50 passing through two hollow shafts 51, 52 on which are

20 mounted respectively the impeller sets II, III, VI and VII. The impeller set II, III on hollow shaft 51 is driven by the pulley 53 from the motor pulley 57; the set I, IV, V, VIII on shaft 50 is driven by pulley 54, the drive including the

25 motor pulley 55 and the reversing idlers 56. The impeller set VI, VII on hollow shaft 52 is driven by pulley 58 from motor pulley 59, and in this way each pair of impellers (I, II), (III, IV), (V, VI), (VII, VIII) has its individual impellers

30 rotating in opposite directions. This combination may also be used for six impellers, for instance, by omitting any desired pair of impellers from the four pairs shown. The shaft 50 is sup-

35 ported within the hollow shafts 51 and 52, and also by central bearing 60 and end bearings 61 and 62. The hollow shaft 51 is journaled in the bearing 63, and hollow shaft 52 in bearing 64, these bearings 60, 63 and 64 being supported

40 from the housing by any desired form of stay members, such as those indicated at 65.

Instead of reversing by idler pulleys, a reversing gearing may be interposed at one end of the motor drive, and where desired the motor drive at each end may be geared down from the ar- 45 mature speed, in which case one of the reduction gearings will be provided with a reversing pinion so as to give drives in opposite directions at the opposite ends of the motor.

In Figs. 9 and 10 a motor 60' is mounted on a base 61' supporting the fan housing 62', the driving belting passing in through orifices 63' of the housing, and the reversal of the drive being provided for by reversing gears contained in the extension housing 64' at the end of the motor 60'.

In Figs. 11 and 12 a further modification is shown in which the motor 65' carries the impellers F, F', the motor being mounted by stays 66' in the casing 67' on base 68'. Reduction 0 gearing is provided between the motor armature and the impeller shafts, this gearing for the im- 5 peller F being enclosed in the casing 69', while the gearing for the impeller F' is enclosed in the casing 70'. The entire motor assembly forms one unit and the reduction gearings are constructed to drive the impellers in opposite directions.

The fan or "impeller-blower" of this invention comprises a pair of cooperating impellers, or a higher number of impellers preferably in pairs, each pair acting to receive the air stream axially and deliver it axially. The first impeller of each pair imparts a rotation to its discharge so that the stream lines between the impellers of each pair are generally helical and with a helix angle

I claim:

1. A fan unit consisting of a housing and a 10 series of coaxial disk fan impellers therein draw- 15 ing a supply of gas at one end of the series, in- creasing the pressure by each impeller rotated under substantially the same torque and dis- charging the gas at the opposite end of the series 15 with substantially no rotation of the discharge around the axis, and means for driving said im- pellers with relatively opposite rotations at sub- 20 stantially the same speed, the impellers rotating in opposite directions having their respective 20 blade widths and blade angles and the number of blades different as to at least one of these features and so related that their torque resist- 25 ances are substantially identical under normal operating conditions. 25

2. A fan unit receiving air axially and deliver- 30 ing it axially with substantially no rotation of the discharge around the axis consisting of a series of pairs of disk impellers, the impellers of each pair rotating in opposite directions with respect 30 to each other, a housing in which said impel- 35 lers are mounted and means for driving said impellers at substantially the same speed, the impellers rotating in opposite directions having their respective blade widths and blade 35 angles and the number of blades different as to at least one of these features and so related that their torque resistances are substantially identi- 40 cal under normal operating conditions. 40

3. A fan unit comprising a pair of coaxial disk fan impellers drawing a supply of gas at one end, passing it through the space between the impellers, and discharging it at the opposite end, the first impeller being adapted to impart a 45 rotation of over 25° to its discharge stream so that the rotational energy in the discharge is proportionately large, and the following impeller being adapted to substantially neutralize said 45 rotation and deliver the stream substantially 50 axially, the impellers rotating in opposite direc- 55 tions having their respective rotary speeds and blade widths and blade angles and the number of blades so related that their torque resistances are substantially identical under normal operating 55 conditions.

4. A fan unit comprising a pair of coaxial disk fan impellers drawing a supply of gas at one end, passing it through the space between the impellers, and discharging it at the opposite end, the first impeller having large angle blades adapt- 60 ed to impart a rotation of over 25° to its dis- charge stream so that the rotational energy in the discharge is proportionately large, and the following impeller having relatively fewer blades 60 at angles smaller than those of the preceding im- 65 peller adapted to substantially neutralize said rotation and deliver the stream substantially ax- 70 ially, the impellers rotating in opposite directions having their respective rotary speeds and blade widths and the number of blades so related that 70 their torque resistances are substantially iden- 75 tical under normal operating conditions. 75

5. A fan unit comprising a pair of coaxial disk fan impellers drawing a supply of gas at one end, passing it through the space between the 75

impellers, and discharging it at the opposite end, the first impeller having blades at angles over 45°, adapted to impart a rotation of over 25° to its discharge stream so that the rotational energy in the discharge is proportionately large, and the following impeller having blades at angles less than 45° adapted to substantially neutralize said rotation and deliver the stream substantially axially, the impellers rotating in opposite directions 10 having their respective rotary speeds and blade widths and the number of blades so related that their torque resistances are substantially identical under normal operating conditions.

6. A fan unit consisting of one or more pairs 15 of disk impellers in series, the impellers of each pair rotating in opposite directions with respect to each other, a housing in which said impellers are mounted and means for driving said impellers, the first impeller of each pair having more blades than the second impeller of the pair, the impellers rotating in opposite directions having their respective rotary speeds and blade widths and blade angles so related that their torque resistances are substantially identical 25 under normal operating conditions.

7. A fan unit consisting of one or more pairs of disk impellers in series, the impellers of each pair rotating in opposite directions with respect to each other, a housing in which said impellers are mounted and means for driving said impellers, the first impeller of each pair having more blades and larger blade angles than the second impeller of the pair, the impellers rotating in opposite directions having their rotary 30 speeds and blade widths so related that their torque resistances are substantially identical under normal operating conditions.

8. A fan unit consisting of pairs of disk impellers in series, the impellers of each pair rotating in opposite directions with respect to each other, a housing in which said impellers are mounted and means for driving said impellers, the first impeller of each pair having larger blade angles than the second impeller of the pair, the impellers rotating in opposite directions having their respective rotary speeds and blade widths 40 and the number of blades so related that their torque resistances are substantially identical under normal operating conditions.

50 9. A four-stage fan unit comprising two pairs of impellers in series, each pair separated by intervening air spaces of greater axial extent than the impeller blades, the impellers of each pair having their individual impellers rotating in

opposite directions and means for driving all of said impellers from a single motor, the impellers rotating in opposite directions having their respective rotary speeds and blade widths and blade angles and the number of blades so related that their torque resistances are substantially identical under normal operating conditions.

10. An eight-stage fan unit comprising four pairs of impellers in series with the individual impellers of each pair rotating in opposite directions, and means for driving all of said impellers from a single motor comprising a shaft for the first, fourth, fifth and eighth impellers and separate shafts for the second and third and sixth 10 and seventh impellers, and a single motor means for driving said first mentioned shaft in one direction and the remaining shafts in the opposite direction, the impellers rotating in opposite directions having their respective rotary speeds and blade widths and blade angles and the number of 15 blades so related that their torque resistances are substantially identical under normal operating conditions.

11. A fan unit comprising, in combination, a housing symmetrical about its axis, disk fans 25 mounted on said axis, driving means suitable for rotating each of the two fans constituting a pair in opposite directions and with speeds having at all times a definitely predetermined ratio, the blading for the first impeller having high 30 blade angles designed to create a pronounced spiral flow, the second impeller having much smaller blade angles, and the blade width and blade area being designed to give the second impeller substantially the same torque in reverse 35 direction as the first impeller and to convert the spiral flow into an axial flow at higher pressure than at entry into the pair.

12. A fan unit comprising, in combination, a housing symmetrical about its axis, disk fans 40 mounted on said axis, driving means suitable for rotating each of the two fans constituting a pair in opposite directions and with speeds having at all times a definitely predetermined ratio, the blading for the first impeller having high blade 45 angles designed to create a pronounced spiral flow, the second impeller having much smaller blade angles and fewer blades, and the blade width and blade area being designed to give the second impeller substantially the same torque in reverse 50 direction as the first impeller and to convert the spiral flow into an axial flow at higher pressure than at entry into the pair.

GEORGE DE BOTHEZAT.
